CLAIM

The ornamental design for a snack container lid for a drinking cup, as shown and described herein.

DESCRIPTION

FIG. 1 is a perspective view of a snack container lid for drinking for showing my new design;

FIG. 2 is a front view thereof;

FIG. 3 is a back view thereof;

FIG. 4 is a first side view thereof;

FIG. 5 is an opposite side view thereof;

FIG. 6 is a top view thereof; and,

FIG. 7 is a bottom view thereof.

The broken lines are shown for the purpose of illustrating both parts of the article as well as the boundaries of the claim. None of the broken lines form part of the claim.

1 Claim, 7 Drawing Sheets
